INVENTOR

George F. Greene

UNITED STATES PATENT OFFICE.

GEORGE F. GREENE, OF PROVIDENCE, RHODE ISLAND.

DESIGN FOR A SCARF-PIN.

SPECIFICATION forming part of Design No. 23,757, dated November 6, 1894.

Application filed October 6, 1894. Serial No. 525,166. Term of patent 3½ years.

To all whom it may concern:

Be it known that I, GEORGE F. GREENE, a citizen of the United States, residing at Providence, in the county of Providence and State of Rhode Island, have invented and produced a new and original Design for Scarf-Pins, of which the following is a specification, reference being had to the accompanying drawing, forming part thereof.

10 The head or ornamental portion of the scarf-pin has the outline, shape and appearance of a curly-haired shepherdess, in front view, wearing a broad-brimmed, small-crowned hat, a bodice laced in front and having bowed ribbon straps extending over the

shoulders, a short skirt caught up at the sides and front and a petticoat or skirt extending to the knees. On her feet appear slippers. One arm is akimbo and the other bent at the elbow, with the forearm up, supports a shepherd's crook. The pin tongue extends centrally downward from said ornamental portion.

What I claim is—

15 The design for a scarf-pin herein shown and described.

GEORGE F. GREENE.
